CLAIM

The ornamental design for a water supply container for pets, as shown and described.

DESCRIPTION

FIG. 1 is a right side elevational view of a water supply container for pets showing my new design;

FIG. 2 is a rear elevational view thereof;

FIG. 3 is a front elevational view thereof;

FIG. 4 is a left side elevational view thereof;

FIG. 5 is a top plan view thereof;

FIG. 6 is a bottom plan view thereof;

FIG. 7 is a cross sectional view thereof taken along line 7—7 of FIG. 4;

FIG. 8 is a perspective view thereof; and,

FIG. 9 is another perspective view thereof.

The broken lines in FIG. 9 are for purposes of illustration only and form no part of the claimed design.
